UNITED STATES PATENT OFFICE.

AMOS CALLESON, OF BROOKLYN, NEW YORK, ASSIGNOR TO ADRIANCE MACHINE WORKS, INC., OF BROOKLYN, NEW YORK, A CORPORATION OF NEW YORK.

BOTTLE-SEALING MACHINE.

1,294,396.

Specification of Letters Patent. Patented Feb. 18, 1919.

Application filed May 28, 1917. Serial No. 171,887.

To all whom it may concern:

Be it known that I, AMOS CALLESON, a citizen of the United States, residing at Brooklyn, in the county of Kings and State of New York, have invented certain new and useful Improvements in Bottle-Sealing Machines, of which the following is a specification.

This invention relates to machines for exerting pressure on containers in connection with such an operation as the affixing of the closures thereto, for instance, and it contemplates certain improvements whereby an easy and regular motion of the moving parts is obtained, lost motion may be eliminated, and greater efficiency in general and improved results in respect to the operations performed on the containers are effected.

In the accompanying drawing, the view shows in vertical section a bottle sealing machine embodying my improvements.

The base *a*; table *b*; pillar *c*; head *d*; carrier *e* on which is bolted or otherwise secured the element *f* on which are suitably arranged the pressure applying sealing head *g* and other parts, said carrier being movable up and down oscillatory on the pillar *c*; the horizontal drive shaft *h* journaled in the head; the lever *i* fulcrumed in the head and having a sliding engagement with the up-standing stud *j* on element *f*; and the rotary bottle advancing turret *k* journaled on the base *a* concentric with the pillar are or may be, except as hereinafter indicated, all substantially the same as in my Patent No. 1,096,527.

The carrier *e* has an inward projection *l* and a stud *m*, equipped with a roller *n*, the pillar being formed with an opening *o* to accommodate and permit movement of the stud and projection with the carrier as the same moves up and down and transversely, as will be explained. Secured to the projection *l* by the bolt *p*, or otherwise, is a sleeve *q* forming in effect a downward extension of the carrier, it being concentric with the pillar and guided by a bearing *r* keyed into the foot of the pillar.

A long shaft *s* extends through the head *d*, an inwardly projecting arm *t* of the pillar (in which arm the shaft is in effect stepped by virtue of its shoulder *t'*) and the sleeve *q*, being threaded at its lower end and supported against lateral movement at its upper end by a plate *u* suitably secured on the head

d. On the lower threaded end of this shaft is screwed a long nut *v* having a shoulder *w* at its lower end and thereby forming a step for a spring *x* which is coiled above the nut and extends up into the sleeve, the upper end of which is reduced and affords at *y* a thrust bearing for the spring. It will be seen, in view of the foregoing, that the carrier is yieldingly supported by the spring *x*, in turn supported by the nut or step *v* which is screwed on the shaft *s* and therefore virtually becomes a fixed part of the frame. The nut is adjustable by turning it on the threaded portion of the shaft, which may be held against rotation for this purpose by the set screw *z*. It is preferred that the upper end of the sleeve *q* be afforded a bearing, as at *2*, on the shaft.

Concentric with the shaft *s* is a hollow shaft or sleeve *3* penetrating the head; the shaft *3* is kept from vertical movement by an anti-friction bearing *4* arranged thereon against a shoulder *5* and bearing against the lower side of the head and an anti-friction bearing *6* arranged thereon above and held against the head by a cam structure *7* keyed on said shaft, such cam structure being adapted, when rotated, to oscillate the lever *i* and hence the carrier substantially the same as in my patent referred to. Below the head shaft *3* carries a barrel cam *8* whose camway *9* faces and is engaged by the roller *n* on stud *m* of the carrier. The shaft *3*, and consequently cam-structure *7* and cam *8*, is rotated from shaft *h* through a worm 10 thereon and a worm-wheel *11* suitably fixed on shaft *3*.

The turret *k* may be rotated from shaft *h* through a vertical shaft *12*, suitably journaled in the head *d* and table *b* and provided with a worm-wheel *13* meshing with the worm *10* and a pinion *14* meshing with gear teeth *15* on the turret.

The operation will be apparent. On shaft *h* being rotated, while the turret is rotatively driven therefrom so as to advance the bottles in a circular course around the base of the pillar, structure *3*, *7*, *8* is driven from shaft *h*, causing, through lever *i*, carrier *e* to oscillate around shaft *s* as an axis and the carrier at intervals to move downwardly, to perform the sealing thrust, the return movement of the carrier being effected by the spring *x*, the resultant of these movements of the carrier being substantially

the same as in my aforesaid patent. The tension of the spring is designed to be adjusted so as to keep the roller n against the face of cam 8, eliminating lost motion, by 5 adjusting the nut or step v on the threaded shaft.

Having thus fully described my invention, what I claim as new and desire to secure by Letters Patent is:—

10 1. In combination, a fixed structure and a reciprocating structure guided by said fixed structure and having a pressure applying head coactive with said fixed structure to exert pressure on a container, and means 15 to reciprocate the second structure including a rotary cam device journaled in the first structure and engaging the second structure and adapted to move the latter in one direction and spring means pressing the second 20 structure in the other direction, the axis of rotation of the cam and the thrust axis of the spring means being substantially coincident and extending longitudinally of the thrust-line of said second structure, said 25 head being offset with respect to the first-named means.

2. In combination, a fixed structure and a reciprocating structure guided by said fixed structure and coactive therewith to exert 30 pressure on a container, the second structure being also rotatable on an axis longitudinal of its line of thrust movement, and means to reciprocate the second structure including a rotary cam device journaled in 35 the first structure and engaging the second structure and adapted to move the latter in one direction and spring means pressing the second structure in the other direction, the axis of rotation of the cam and the 40 thrust-axis of the spring means being substantially coincident with the axis of rotation of said second means.

3. In combination, a fixed structure and a reciprocating structure guided by the 45 fixed structure and coactive therewith to exert pressure on a container, a cam engaging the reciprocating structure and adapted

to move the same in one direction and journaled on an axis extending longitudinally of the path of movement of said reciprocating structure, and a spring interposed between said structures and adapted to move the reciprocating structure in the other direction, one of said structures having spring-adjusting means rotative on said axis. 55

4. In combination, a fixed structure and a reciprocating structure guided by said fixed structure and coactive therewith to exert pressure on a container, the first structure having a shaft extending longitudinally of the thrust of the second structure and a step adjustable longitudinally of and on the shaft, and means to reciprocate the second structure including a cam device journaled in the first structure and 60 engaging the second structure and adapted to move the latter in one direction and spring means bearing against said step and pressing the second structure in the other direction. 65

5. In combination, the frame having an upstanding hollow pillar, a carrier movable up and down on and arranged exterior of the pillar, said frame having a step axial of the pillar, means to move the carrier in one 70 direction including a rotary cam within and coaxial with the pillar and engaging the carrier, and a spring within the pillar pressing the carrier in the other direction and bearing against said step. 75

6. In combination, the frame having an upstanding hollow pillar, a carrier movable up and down on and arranged exterior of the pillar, said frame having a step axial and adjustable longitudinally of the pillar, means to move the carrier in one direction including a rotary cam within and coaxial with the pillar and engaging the carrier, and a spring within the pillar pressing the carrier in the other direction and bearing 80 against said step. 85

In testimony whereof I affix my signature.

AMOS CALLESON.
